CLAIM

The ornamental design for an electric oven, as shown and described.

DESCRIPTION

FIG. 1 is a perspective view of an electric oven, showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the electric oven shown in an alternate position in which the handle of the lower door is pulled out;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is a perspective view of the electric oven shown in another alternate position in which the lower door is opened;

FIG. 16 is a front view thereof;

FIG. 17 is a rear view thereof;

FIG. 18 is a left side view thereof;

FIG. 19 is a right side view thereof;

FIG. 20 is a top view thereof; and,

FIG. 21 is a bottom view thereof.

The dashed broken lines illustrating portions of the electric oven form no part of the claimed design. The long-dash,

(Continued)

short-dash broken lines illustrate a boundary of the claimed design and form no part of the claimed design.
